APPARATUS FOR FORMING WATER
HEATING COILS

Winford L. Enghauser, Cincinnati, Ohio, assignor
to The Production Plating Works, Inc., Leb-
anon, Ohio, a corporation of Ohio

Application December 5, 1938, Serial No. 243,908

5 Claims. (Cl. 153—33)

This invention relates to the art of bending or forming lengths of tubing and is particularly directed to apparatus for bending a length of pipe into the form suitable for a water coil, specifically providing a reversely bent length of tubing having parallel runs and adjacent terminal ends. It is desirable to extend the amount of passageway so that the water has a greater travel in the zone of heat. For this reason, the tube is bent so as to provide an enlarged or flared bight.

The formation of a coil of this shape presents unusual problems in the art of bending. One of the first considerations is reduction in the number of steps required in the formation. The coil must sell inexpensively and it is therefore desirable that the number of steps be reduced to a minimum to save costs of production. Also the tubing must be supported efficiently during the bending so as to prevent wall collapse.

It has been the object of the present inventor to provide an apparatus for bending a length of tubing into a complete coil in a single operation or pass. A structure, resulting from this objective, may consist of a throated die, including a 25 rocking die actuated by the motion of a descending forming die as it passes into the throat of the lower die for bending the pipe around the forming element of the descending die to form the enlarged bight and for disposing the runs in 30 close proximity.

It has been a further object of the inventor to facilitate the removal of the finished coil from the apparatus. Toward this end, the equipment includes a release mechanism whereby the forming parts may be moved a predetermined amount to permit the withdrawal of the finished coil.

It has also been an object of the inventor to provide an apparatus of this character which is rugged and accurate in the production of the article, which adequately supports the tubing, and wherein the forming parts may be interchanged to produce coils formed of pipe of different diameters.

The method described herein forms the subject matter of a divisional application, Serial No. 304,984, filed November 17, 1939.

Other objects and certain advantages will be more fully apparent in a description of the accompanying drawings in which:

Figure 1 is the front view of the coil forming apparatus of this invention.

Figure 2 is a fragmentary view taken similar to Figure 1 but showing the apparatus in position after forming the length of tubing into a coil.

Figure 3 is a side view of the apparatus.

Figure 4 is an enlarged sectional view taken on line 4—4, Figure 1, illustrating the details of the top die.

Figure 5 is an enlarged fragmentary view of a portion of Figure 3, further detailing the die.

Figure 6 is a view taken similar to Figure 5, but showing the release mechanism thereof operated for removing the finished coil.

Figure 7 is a sectional view taken on line 7—7. 5 Figure 5, further detailing the release mechanism.

Figure 8 is a sectional view taken on line 8—8, Figure 1, detailing a portion of the lower die.

Generally described, the apparatus consists of 10 a stationary die having a rocking die pivoted thereon, and an upper die adapted to descend upon the pipe for forcing the pipe between the stationary die and the rocking die and causing the rocking die, by virtue of its rocking motion, to form the coil around the forming wheel of the descending die.

Specifically referring to the drawings, the apparatus consists of a base or pedestal 10. The lower die support or continuation of the base is indicated at 11. The stationary die 12, is fitted in a recess in the inner side wall of the throat 13 of the die support 11. Specifically, the die element 12 consists of an angular base, the top arm of which rests on the top surface of the die support. This die element is removable for interchange. A separate die element for each size of tubing is employed. A semi-circular groove 14, formed on the radius of the particular tubing, extends along the top arm and the side arm of the die and feathers out at the base of the vertical arm.

A bracket 15, for supporting the length of the pipe, is fixed against the side of the support and provides a horizontal arm, the top surface of 35 which lies in the plane of the base of the semi-circular groove 14. This arm has a stop 16 adjustably fixed thereon by means of a set screw 17. The length of tubing, indicated at 18, has one end engaged against this stop 16.

The rocking die 19 is constituted by a bell crank, which is pivoted on a pivot pin 20. One arm of the bell crank extends upwardly and carries a forming wheel 21, which includes a semi-circular groove 22, formed on the radius of the particular tubing, wherein the wheel is in the form of a sheave. When this wheel is in upward position, the straight length of pipe will rest tangentially in the groove since the base of the groove is in the same plane as the base of the groove of the stationary die.

The horizontal arm of the bell crank carries an actuating wheel 23. This wheel is grooved in the same manner as the wheel 21. The wheel is disposed directly in the path of the descending die 55 or, more specifically, the pipe pressed downwardly under the die. The bell crank is held in the position as described above by means of a coil spring 24 under tension between a pin 25 on the vertical arm and a pin 26 fixed on a stop element 27 attached to the side of the support 11. The bell crank carries a stop 28 engaged with stop 27

when the rocking die is in position prior to descent of the upper die.

The details of the die actuating mechanism are not shown since they are conventional. The lower end of the ram 29 includes an attachment flange 30. The carrier bracket 31 for the upper forming wheel 32, includes an attaching flange 33 corresponding to that of the ram and attached thereto by means of screws 34. The downwardly extending portion of the bracket 31 includes the forming wheel 32 attached against its side by means of a stud 35. The forming wheel 32 is of the same type as the wheel 21 but is split centrally of its thickness, that is, at right angles to its axis. The stud is fixed rigidly in position and the wheel sections are loosely mounted on the stud.

The outer section 36 of the wheel is shiftable along the stud by means of a lever 37. The handle 38 of the lever is screwed into one arm of a bell crank 39, which is bifurcated and pivoted on the outer end of the stud 35 on a pin 40. The other arm of the bell crank is connected to the wheel by means of a link 41. For this purpose, the wheel section 36 includes spaced ears extending longitudinally of the stud at each side thereof. The link elements 41 in each instance, are attached to the inner side of the ears 42 by means of screws 43. The screws afford a pivotal connection since they are screwed into the ears and loosely engage the links. The same arrangement is provided for attaching the links to the bifurcated arm of the bell crank, the screw, in this instance, being indicated at 44.

Thus, when the pivot 40 and the screws 43 and 44 are aligned along the axis of the stud, the sections of the wheel are held together as indicated in Figure 5. In this position, inward movement of the lever 37 is limited by means of a set screw 46 traversing a cross piece 47 of the bell crank lever and held in position by means of a nut 48 whereby the set screw will engage the stud (see Figure 7) when the wheel is ready for the forming operations.

The ram is held in spaced relation with respect to the stationary die and against any spreading tendency by means of a roller 50 carried by an arm 51 fixed to the carrier for the upper forming wheel. This roller rides along the outer surface of a guide bar 52 fixed vertically to the rear face of the base 11.

An adjustable stop 55 is fixed to the ram and includes a wheel 56 appropriately grooved and adapted to be engaged by the run of tubing when the ram reaches the lower end of its stroke for maintaining the formed run in strictly vertical position (see Figure 2).

When the forming wheel is in the position shown in Figure 6, the finished coil may be slid downwardly, assuming, of course, that the ram 60 has been raised. The runs 57 of the coil are spaced sufficiently to permit traversal with respect to the stud 35.

Having described my invention, I claim:

1. An apparatus for forming a length of tubing into a reversely bent element, comprising; a base including a throat, a support disposed horizontally at one side of the first named support, a bell crank pivoted on the support at the side opposite to the support, one arm of said bell crank extending upwardly, a forming wheel mounted thereon, and disposed in the same plane as said support, a forming die adapted to descend into the throat, a forming wheel on said

die adapted to engage the tubing, said bell crank having one of its arms extended laterally into the throat and engageable by the descending tubing for causing the first named forming wheel to bend the tubing around the descending forming wheel and to move one run of tubing close to the other, and means for spreading the descending forming wheel to permit removal of the formed element.

10 2. An apparatus for forming a length of tubing into a reversely bent element, comprising; a support including a throat, a bell crank pivoted on the support at one side of the throat, one arm of said bell crank extending upwardly, a forming wheel mounted thereon, a forming wheel adapted to be moved into the throat, said bell crank having one of its arms extended into the throat and engageable by the descending tubing for causing the first named forming wheel to bend the tubing around the descending forming wheel.

15 3. An apparatus for forming a length of tubing into a reversely bent element, comprising; a support including a throat, a bell crank pivoted on the support at the side opposite to the second named support, one arm of said bell crank extending upwardly, a grooved forming wheel mounted thereon and disposed in the same plane as the top of the support, a grooved forming wheel adapted to enter the throat and engage the tubing, said bell crank having one of its arms extended laterally into the throat, an actuating wheel on said arm engageable by the descending tubing for causing the first named forming wheel to bend the tubing around the descending forming wheel and to move the one run of pipe close to the other, and means for spreading the descending forming wheel to permit removal of the formed article.

20 4. In a pipe bending apparatus, a support for the pipe including a throat, a forming die adapted to descend into said throat and including a grooved forming wheel for direct engagement with the pipe, guide means for holding the forming wheel toward one side wall of the throat, a bell crank having one arm engaged as the forming wheel descends and the other arm carrying a grooved forming wheel for bending the pipe around the first named forming wheel whereby the bend of the pipe is greater than 180 degrees, means for normally holding the bell crank with the last named forming wheel clear of the throat and, means disposed on the die for controlling the spacing and maintaining the parallelism of the runs of pipe.

25 5. A pipe bending apparatus adapted to bend a length of tubing into a reversely bent form, comprising a support including a throat, a bell crank pivoted on the support at one side of the throat, one arm of said bell crank extending upwardly, a forming disc mounted on the upper end of said arm and disposed in the plane of the top of the support for providing a supporting surface for the length of tubing, a forming means adapted to descend into the throat, including a circular forming disc on its lower end, said bell crank including an arm extending laterally into the throat and adapted to be engaged as the forming disc descends, for causing the first-named forming disc to bend the tubing around the descending forming disc.
